UNITED STATES PATENT OFFICE

149,343

DESIGN FOR A BATHING SUIT

Mary Ann De Weese, Glendale, Calif.

Application September 13, 1946, Serial No. 133,293

Term of patent 14 years

(Cl. D3—17)

To all whom it may concern:

Be it known that I, Mary Ann De Weese, a citizen of the United States, residing at Glendale, in the county of Los Angeles and State of California, have invented a new, original, and ornamental Design for a Bathing Suit, of which the following is a specification, reference being had to the accompanying drawing, forming a part thereof.

Fig. 1 is a front perspective view of a bathing suit showing my new design, and

Fig. 2 is a rear perspective view thereof.

I claim:

The ornamental design for a bathing suit, as shown.

MARY ANN DE WEESE.
